UNITED STATES PATENT OFFICE.

CHARLES GIBBONS LUDLOW, OF CHICAGO, ILLINOIS, ASSIGNOR TO THE CROSBY
STEAM GAGE AND VALVE COMPANY, OF BOSTON, MASSACHUSETTS.

DEVICE FOR ATTACHING PRESSURE-GAGES TO BOILERS.

SPECIFICATION forming part of Letters Patent No. 495,594, dated April 18, 1893.

Application filed January 22, 1892. Serial No. 418,923. (No model.)

To all whom it may concern:

Be it known that I, CHARLES GIBBONS LUDLOW, a citizen of the United States, residing at Chicago, in the county of Cook and State 5 of Illinois, have invented certain new and useful Improvements in a Device for Attaching Pressure-Gages to Steam-Boilers; and I do hereby declare the following to be a full, clear, and exact description of the invention, such 10 as will enable others skilled in the art to which it appertains to make and use the same.

The object of the present invention is to so attach steam gages to boilers that steam will not enter the gage, and the invention consists 15 in the construction hereinafter pointed out.

Referring to the drawings: Figure 1 represents a steam boiler of the ordinary type, showing this improved method of attachment of the steam gage to it, so that water only of 20 the boiler flows into it. Fig. 2 represents a cross section through the line 2—2 as appears in Fig. 1. Fig. 3 represents an enlarged view of the rear portion of the valve, D, in elevation. Fig. 4 represents a longitudinal sectional view of the valve, D, through line 4—4, Fig. 3. Fig. 5 represents a horizontal sectional view of valve, D, through the line 5—5, Fig. 3.

In the annexed drawings: The letter A indicates a boiler having the water line, *a a*.

The letter B indicates an ordinary steam gage, the pipe, C, of which communicates with the boiler, A, below the water line, *a a*, as shown. At a convenient point this pipe, C, is 35 provided with a trap, D. The main portion, *d*, of this trap, D, has its end, *d'*, tapped into the boiler with the interior of which the bore, *d²*, of the trap, D, communicates. Leading into this bore, *d²*, is a hole, *d³*, closed by a plug, 40 *d⁴*. At a right angle to the bore, *d²*, and communicating therewith, is another bore, *e²*, the

bores, *d²* and *e²*, forming a passage through the trap, D. The bore, *e²*, is made in an upturned portion, E, of the trap, D, and to this portion, E, is secured a coupling, F, for the 45 pipe, C, leading to the steam gage, B. At the angle of the trap, D, is formed a cup, G, having the threads, *g*, whereto is held a plug, H, carrying the valve, I. This plug, H, does not completely fill the cup, G, but there is a small 50 chamber, *g*, which communicates with the outer air by a hole, *g'*, and with the bore, *d²*, of the trap, D, by a passage, *g²*, this passage being closed by the valve, I. With such an attachment as this there is always a column 55 of water in the pipe, C, and, therefore, steam never enters the gage, B.

Should there be any sediment in the trap, D, it may be blown out through the passage, *g²*, chamber, *g*, and hole, *g'*. The valve, H, is 60 normally closed, but may be opened to allow of the "blow off." Scale may be removed through the hole, *d³*, by removing the plug, *d⁴*.

Having thus described my invention, what I claim is—

The combination of a boiler; a steam gage; and a pipe leading from the boiler to the gage; with a trap D erected in said pipe below the water line of the boiler, such trap having the bores *d²* *e²* communicating with each other, 70 the cup G having the chamber *g* communicating with the bore *d²* by passage *g²* and with the outer air by the hole *g'*; the valve I controlling the passage *g²*, and a plug *d⁴* closing the hole *d³* leading into the bore *d²* as set forth. 75

In testimony whereof I affix my signature in presence of two witnesses.

CHARLES GIBBONS LUDLOW.
